CLOTHES CATCHING ATTACHMENT FOR
IRONING BOARDS

Alice J. Blumenshien, National City, Calif.

Application July 5, 1949, Serial No. 103,041

1 Claim. (Cl. 38—111)

1

My invention relates to a clothes catching attachment for ironing boards, more particularly to an improvement over my co-pending application for clothes catching attachment for ironing boards, Serial No. 74,833, filed February 5, 1949, and the objects of my invention are:

First, to provide a clothes catching attachment for ironing boards of this class which may be readily folded and maintained in connection with a conventional folding ironing board when not in use and in folded position;

Second, to provide a clothes catching attachment of this class which is very simple and easy to operate, and to fold into position which permits the folding of the ironing board to which it is attached;

Third, to provide a clothes catching attachment of this class which is very readily and easily changed to permit the placement of clothing over the end of the ironing board when desired;

Fourth, to provide a clothes catching attachment of this class having very simple means for supporting and detaching the hamper thereof;

Fifth, to provide a clothes catching attachment of this class having supporting arms pivoted in connection with the lower side of the ironing board which may be pivoted into contiguous relationship with the lower side of the board and parallel thereto, so that tubular-shaped clothing, such as dresses, skirts or the like may be placed in surrounding relationship with the ironing board substantially its entire length;

Sixth, to provide a clothes catching attachment for ironing boards of this class which is very simply and readily attached to various conventional ironing boards of the folding type now in use; and

Seventh, to provide a clothes catching attachment for ironing boards of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, forming a part of this application, in which:

Fig. 1 is a top or plan view of an ironing board, showing my clothes catching attachment for ironing boards in connection therewith; Fig. 2 is an enlarged fragmentary side elevational view taken from the line 2—2 of Fig. 1; and Fig. 3 an end

2

view of the ironing board as shown in Fig. 1, showing my clothes catching attachment in connection therewith, and showing the hamper thereof fragmentarily.

5 Similar characters of reference refer to similar parts and portions throughout the several views of the drawings.

The ironing board 1, arm members 2, 3, 4 and 5, rods 6 and 7, and the flexible hamper 8, constitute 10 the principal parts and portions of my clothes catching attachment for ironing boards.

The ironing board 1 is substantially conventional, and may be of the conventional type having folding legs which collapse into contiguous 15 relationship with the lower surface of said board 1. Pivoted secured to the lower surface of the ironing board 1 are the arm members 2 and 3, which are preferably flat strap arms adapted to be shifted as indicated by dash lines in Fig. 1, 20 of the drawings, into contiguous parallel relationship with the lower surface 1a of the board 1, as shown in Fig. 3 of the drawings. Pivoted secured to the arms 2 and 3 by means of pins 2a and 3a are the arm members 4 and 5. The arms 25 4 and 5 are provided with openings 4a and 5a, respectively, in their extending end portions, through which opposite ends of the rod 6 extend downwardly.

As shown in Fig. 2 of the drawings, the arm member 4, fixed to the arm member 2, extends 30 at right angles to the board 1 and the downwardly extending end 6a of the rod 6 extends through the opening 4a from which it may be readily removed, as desired. The rod 7 is similar in construction to the rod 6 and opposite ends thereof extend downwardly through openings 2b and 3b of the arm members 2 and 3, as shown in Fig. 1 of the drawings.

The flexible hamper 8 is preferably made of fabric, or other suitable material, and is provided 40 with separate hem portions 8a and 8b, which are fitted over the rods 7 and 6, respectively, as shown in Fig. 3 of the drawings. Intermediate the portions 8a and 8b the flexible hamper extends downwardly in U-shaped form and it is adapted to 45 receive clothing ironed on the board 1, which extend thereover at one side of the board 1 during ironing operations.

The operation of my clothes catching attachment for ironing boards is substantially as follows:

When in use, as shown in Fig. 1 of the drawings, the long pieces of laundry, such as sheets or other similar lengthy articles being ironed on the board 1, may be permitted to extend over 55 the side thereof and into the hamper 8, which

prevents the clothing from falling on the floor and becoming soiled. When it is desired to place a dress or other tubular-shaped garment over the small end 1b of the ironing board 1, the rods 6 and 7 are disengaged from their ends within the openings 3b and 5a of the arm members 3 and 5, and these arm members 3 and 5, as indicated by dash lines in Fig. 1 of the drawings, are pivoted into position parallel with and contiguous to the lower side of the ironing board 1. Thus, the tubular garment is permitted to extend substantially the full length of the board 1 in surrounding relationship therewith. When it is desired to substantially collapse the clothes catching attachment, permitting the legs of the ironing board to be folded and placed in a closet or the like, the rod 6, at its opposite ends, may be placed in holes 2c and 3c of the arm members 2 and 3, adjacent the rod 7. The hamper 8 may then be folded over the upper surface of the board 1 and the arms 4 and 5 may be pivoted into parallel relationship with the rods 6 and 7, so that the entire clothes catching attachment is very compact and may be retained in adjacent relationship to the ironing board 1 by cross straps or other fixtures, as desired. It is to be noted that the collapsed arrangement of the clothes catching attachment does in no way limit or prevent the folding or collapsing of the conventional ironing board folding legs. Thus, my clothes catching attachment may be maintained in connected relationship with the ironing board at all times, whether in use or stored in a closet or conventional cabinet.

Though I have shown and described a particular construction, combination and arrangement of parts and portions, I do not wish to be limited to this particular construction, combination and arrangement, but desire to include in the scope

of my invention the construction, combination and arrangement substantially as set forth in the appended claim.

Having thus described my invention, what I claim as new and desire to secure by Letters Patent is:

In a clothes catching attachment for ironing boards, an ironing board having substantially flat upper and lower surfaces, an arm member pivoted on a vertical axis to the lower surface thereof near each end thereof, a secondary arm member pivotally connected to each of said first-mentioned arm members near each end of said ironing board, each of said arm members having a pair of spaced vertical openings therein disposed outwardly of the side of said ironing board, a pair of rods having horizontal hamper supporting portions and vertically disposed end portions fitted in said openings, extending intermediate and supported by said arm members, one of said rods interconnecting said first-mentioned arm members, the other of said rods interconnecting said secondary arm members, and a flexible hamper having individual hem portions fitted over said rods and extending in U-shaped form outwardly from the side of said ironing board.
